John Kirby Jr.

UNITED STATES PATENT OFFICE.

JOHN KIRBY, JR., OF DAYTON, OHIO, ASSIGNOR TO THE DAYTON MANUFACTURING COMPANY, OF DAYTON, OHIO.

CAR BASKET-RACK.

SPECIFICATION forming part of Letters Patent No. 787,456, dated April 18, 1905.

Application filed December 24, 1904. Serial No. 238,246.

To all whom it may concern:

Be it known that I, JOHN KIRBY, Jr., a citizen of the United States, and a resident of the city of Dayton, in the county of Montgomery, in the State of Ohio, have invented certain new and useful Improvements in Car Basket-Racks; and I do hereby declare the following to be a full, clear, and exact description of the invention, such as will enable others skilled in the art to which it appertains to make and use the same, reference being had to the accompanying drawings, and to the figures of reference marked thereon, as forming a part of this specification.

My invention relates to improvements in car basket-racks, and has for its principal object the construction of a rack in which the bottom member forms a complete single structure which can be attached to and detached from the wall-brackets when the latter are secured in position on the wall of the car or other support, thereby making it unnecessary to remove the brackets from their support when it is necessary to make repairs to the bottom member of the rack or when for any purpose it is desired to separate the same from the brackets when the rack is in position for use in the car, the invention being especially advantageous when employed in connection with a number of sections forming what is commonly known as "continuous racks," and in which to remove a bottom section it has heretofore been necessary to begin at one end of the rack and remove the brackets and bottom sections until the particular section to be removed for repair or otherwise is reached, while with my improvement any bottom section can be removed and replaced without disturbing any of the other sections or removing any of the brackets from their position on the wall of the car.

To this end and with a view to convenience in manufacture my invention consists in certain details of construction and combination of parts, as will be hereinafter described, and pointed out in the claims at the end of this specification.

In the accompanying drawings, which form a part hereof, Figure 1 is a front view of one full section and a portion of another in position on the wall of the car. Fig. 2 is an end view of Fig. 1. Fig. 3 is a perspective plan view of one of the bottom sections complete and detached from the brackets. Fig. 4 is a side elevation of one of the intermediate connecting-bars. Fig. 5 is an enlarged sectional detail view showing the manner in which the bottom member is connected with the brackets at each end of each of the front and back rods of each section, and Fig. 6 is a sectional view showing the manner in which the ends of the intermediate rods are united with the end connecting-bars.

In the said drawings similar numerals indicate corresponding parts throughout the several figures thereof.

Of the said numerals, 1 and 1' represent the wall-brackets, which are provided with feet 2 and 2', by which the brackets are secured to the wall of the car. These brackets are also provided with screw-threaded projecting members 3 and 3', the end brackets 1 each having two such members on the inside thereof, and the intermediate brackets 1' each having two such members on each side thereof.

The bottom section of the rack is composed of a number of rods 4, 4', and 5, united to form a single structure by means of connecting-bars 6, intermediate bars 7 being employed where it is desired to give additional stiffness to the structure. The front and back rods 4 and 4' are preferably of larger diameter than the rods 5 and may be either tubular or solid. They are provided at each end with shoulders or collars 8, which may be formed thereon in various ways. I prefer, however, to employ tubes for these rods and to plug the ends thereof with plugs 9, having the shoulders 8 formed thereon, as shown in Fig. 5. The intermediate rods 5 are also preferably of tubing, mounted over iron rods 10, screw-threaded at each end and extending through the end connecting-bars 6, the ends of the rods 5 bearing against the

inner sides of said bars and the rods being secured thereto by nuts 11, which engage the threaded ends of the iron rods 10 and bind the whole together, as clearly shown in Fig. 6, the bars 6 and 7 being perforated at 12 to slip over the rods 4 and 4' and the bars 7 being perforated at 13 for the passage therethrough of the rods 5. When the bottom is formed in the manner above described, the connecting-bars may be soldered or otherwise secured to the rods to prevent slipping and to contribute stiffness to the structure.

When the racks are to be made up in separate sections—that is to say, when one bottom section and two ends constitute a complete rack—the wall-brackets are provided on the inside thereof with the screw-threaded members 3, as shown in the left-hand section of Fig. 5, and when the racks are to be continuous the members 3 and 3' are employed at each side of each of the intermediate brackets 1', as shown in the right-hand section of said Fig. 5. The members 3 are provided with screw-threaded shanks 14, which pass through perforations 15 in the brackets, to which at the outer ends of the rack they are secured by tips 16, while at the intermediate brackets (when the racks are continuous) the member 3' is employed to perform the same function, as will be clearly understood by reference to said Fig. 5 of the drawings. It will, however, be apparent that the members 3 and 3' may be cast or otherwise formed on the brackets; but I prefer the construction which I have shown and described.

To connect the bottom section and the wall-brackets together, a coupling 17, having an inwardly-disposed flange 18, is employed at each end of each of the rods 4 and 4' and are movable thereon. These couplings are interiorly screw-threaded to engage the members 3 and 3', and when screwed to place thereon their flanges 18 will engage the collars 8 of the rods 4 and 4' and form a substantial union of the bottom section and the brackets, and when the rack is secured to the wall of the car or other support the bottom sections can readily be detached and removed from the brackets, whether in single or continuous racks, and in the latter case each bottom section can be removed independent of all the other sections, thus saving time and labor, affording economy in manufacture, and contributing convenience in mounting and dismounting the racks.

In carrying out my invention it is obvious that the construction which I have shown and described may be departed from in various ways without departing from the spirit thereof and which consists in a construction that permits of the bottom member being removed from the brackets when the latter are secured to the wall of a car or other support

without disturbing the brackets. Therefore I do not wish to limit the invention to the exact construction herein shown and described.

Having thus fully described my invention, I claim—

1. A basket-rack comprising a bottom member and brackets forming the ends of the rack-section and having provision for attaching the same to a suitable support, in combination with mechanism for coupling the said bottom member to said brackets, the said mechanism being located at the insides of said brackets and wholly within the rack-section.

2. A basket-rack comprising a bottom member consisting of a single structure and brackets forming the ends of the rack-section and having provision for attaching the same to a suitable support, in combination with mechanism for coupling the said bottom member to said brackets, the said mechanism being located at the insides of said brackets and wholly within the rack-section.

3. In a basket-rack, the combination with end brackets therefor, of a bottom member comprising in part a front and a back rod, an enlarged shoulder at each end of each of said rods, and coupling mechanism between said shoulders and the adjacent sides of their respective brackets for coupling the said bottom member and said brackets together, substantially as and for the purpose set forth.

4. In a basket-rack the combination with end brackets therefor, of a bottom member comprising a front and a back rod and a plurality of intermediate rods, connecting-bars by which the said rods are united to form a single structure, enlarged shoulders at each end of each of said front and back rods, and coupling mechanism between said shoulders and the adjacent sides of their respective brackets for coupling the said bottom member and said brackets together, substantially as and for the purpose set forth.

5. In a basket-rack, the combination with end brackets therefor, of a bottom member comprising a front and a back rod and a number of intermediate rods, connecting-bars, by which the said rods are united to form a single structure, enlarged shoulders at each end of the said front and back rods, screw-threaded members projecting laterally from each of said brackets, and screw-threaded couplings which engage the said members and which are provided with inwardly-disposed flanges adapted to engage the said shoulders and whereby the said bottom member and the said brackets are coupled together, substantially as and for the purpose set forth.

6. In a basket-rack, the combination with end brackets therefor, of a bottom member comprising in part a front and a back rod, enlarged shoulders at each end of said rods,

- 5 screw-threaded members projecting laterally from each of said brackets, and screw-threaded couplings which engage the said members and which are provided with inwardly-disposed flanges adapted to engage the said shoulders and whereby the said bottom member and the said end brackets are coupled together, substantially as and for the purpose set forth.
- 10 7. A basket-rack comprising a bottom member and brackets forming the ends of the rack and having provision for rigidly attaching the same to a suitable support, in combination with coupling mechanism located at the ends of said bottom member and on the adjacent sides of said brackets for coupling the said parts together, whereby the said bottom member can be secured in and removed from its position between said brackets without removing either of the latter from their support.
- 15 8. A basket-rack comprising a bottom member consisting of a single structure and brackets forming the ends of the rack and having provision for rigidly attaching the same to a suitable support, in combination with coupling mechanism located at the ends of said bottom member and on the adjacent sides of said brackets for coupling the said parts together, whereby the said bottom member can be secured in and removed from its position between said brackets without removing either of the latter from their support.
- 20 9. A basket-rack comprising a bottom member and brackets forming the ends of the rack and having provision for attaching the same to a suitable support, in combination with screw-threaded members attached to or forming part of and extending laterally from each of said brackets toward the center of the bottom member to be coupled thereto, and couplings which engage the said screw-threaded members and the said bottom member to couple the latter to said brackets, whereby the said bottom member can be secured in and removed from its position between said brackets without removing either of the latter from their support.
- 25 10. A basket-rack comprising a bottom member consisting of a single structure and brackets forming the ends of the rack and having provision for attaching the same to a suitable support, in combination with screw-threaded members attached to or forming part of and extending laterally from each of said brackets toward the center of the bottom member to be coupled thereto, and couplings which engage the said screw-threaded members and the said bottom member to couple the latter to said brackets, whereby the said bottom member can be secured in and removed from its position between said brackets without removing either of the latter from their support.
- 30 11. In a basket-rack, the combination of end brackets adapted to be secured to a suitable support, screw-threaded members attached to or forming part of and extending laterally from said brackets, connecting-rods between said members and whose ends abut the ends thereof, a bottom member intermediate the said rods and connected therewith, and coupling mechanism for uniting the ends of said rods with said screw-threaded members; whereby the entire bottom of the rack can be secured in and removed from its position between said brackets without removing either of the latter from their support.
- 35 12. In a continuous basket-rack comprising a plurality of sections, a separate bottom member for each section, and brackets therebetween; in combination with means for coupling the ends of said bottom members to the adjacent sides of their respective brackets independently of each of the others of said sections, whereby each bottom member can be secured in and removed from its position between said brackets without removing either of the latter from their support.
- 40 13. In a continuous basket-rack comprising a plurality of sections, a separate single-structure bottom member for each section, and brackets therebetween, in combination with means for coupling the ends of said bottom members to the adjacent sides of their respective brackets independently of each of the others of said sections, whereby each bottom member can be secured in and removed from its position between said brackets without removing either of the latter from their support.
- 45 14. As a new article of manufacture, a basket-rack bottom comprising a plurality of rods and an intermediate member, said rods having a shoulder at each end thereof, couplings on said rods which engage the said shoulders and which are adapted to couple the said rods with suitable end brackets, substantially as and for the purpose set forth.
- 50 15. As a new article of manufacture, a basket-rack bottom comprising a single structure in which there are two outer parallel rods provided with an enlarged shoulder at each end thereof, in combination with screw-threaded couplings on said rods having in-turned flanges adapted to engage the said shoulders and whereby the bottom may be coupled to suitable end brackets, substantially as and for the purpose set forth.
- 55 16. As a new article of manufacture, a basket-rack bottom consisting of a plurality of parallel rods united by cross-bars to form a single structure, enlarged shoulders at the ends of the outer of said rods, and couplings which engage the said shoulders and by which

the said bottom may be coupled to suitable end brackets, substantially as and for the purpose set forth.

17. As a new article of manufacture, a basket-rack end provided with laterally-projecting screw-threaded members, substantially as and for the purpose set forth.

In testimony that I claim the foregoing as

my own I have hereunto affixed my signature, this 20th day of December, 1904, in the presence of two witnesses.
